UNITED STATES PATENT OFFICE.

ERNST F. W. ALEXANDERSON, OF SCHENECTADY, NEW YORK, ASSIGNOR
TO GENERAL ELECTRIC COMPANY, A CORPORATION OF NEW YORK.

ALTERNATING-CURRENT GENERATOR.

No. 839,358.

Specification of Letters Patent.

Patented Dec. 25, 1906.

Application filed May 6, 1905. Serial No. 259,066.

To all whom it may concern:

Be it known that I, ERNST F. W. ALEXANDERSON, a subject of the King of Sweden and Norway, residing at Schenectady, county of Schenectady, State of New York, have invented certain new and useful Improvements in Alternating-Current Generators, of which the following is a specification.

My invention relates to alternating-current generators; and its object is to provide a simple and efficient self-exciting alternating-current generator capable of operating over wide ranges both of current and of voltage.

One kind of work to which a generator arranged in accordance with my invention is especially applicable is for thawing water-pipes. For such a purpose an alternating-current generator is better suited than a direct-current generator, not only because of the comparative absence of electrolytic effects, but also because it is very difficult to design a direct-current generator which will operate sparklessly over wide ranges of current and voltage. If an alternating-current

generator is used, it is extremely desirable that it should be self-exciting, for with small machines, such as would be used for this class of work, a separate exciter would add greatly to the cost. It has been proposed

heretofore to make alternating-current generators self-exciting by providing them with a rectifying-commutator and with an auxiliary exciting-winding carried by the armature and connected to the field-winding

through the commutator. A generator so arranged has essentially the characteristics of a shunt-machine, and, as is well known, a shunt-generator will not maintain its voltage if the resistance of the work-circuit is lowered

beyond certain limits. In such work as thawing water-pipes it will sometimes happen that the resistance in the work-circuit is exceedingly low, since a short pipe of large diameter acts almost as a short circuit upon

the machine. Consequently self-exciting generators of the type mentioned above, as ordinarily arranged, would lose their excitation and could not be used for the purpose in view unless resistances were placed in the

work-circuit or some compounding means were employed. The use of resistances would greatly reduce the efficiency and maxi-

mum output of the machine, while compounding in a small alternating-current generator adds greatly to the complication and expense.

By my invention I am enabled to obtain currents of great magnitude at exceedingly low voltages without the use of resistances in the work-circuit or compounding of any kind. I accomplish this result by dividing the armature-winding into a plurality of relatively displaced sections, all or a portion of which may be connected in varying relations to the work-circuit. With a machine thus arranged ordinary variations in the current and voltage desired may be obtained by connecting the armature-sections in different relations to the work-circuit, supplementing these variations by manipulation of the field-rheostat. When currents of large amount and low voltage are required, as in the case of a short pipe of large diameter, I cut out of circuit the sections of the armature-winding on part of the armature. A portion of the armature is thus rendered idle, as far as supplying the work-circuit is concerned, and consequently the armature reaction, which by weakening the field is the cause of the loss of excitation in machines as ordinarily arranged, is substantially eliminated at the idle portions of the armature, which portions may be employed for generating the exciting voltage. Consequently substantially full voltage is induced in the auxiliary exciting-winding at the idle portions regardless of the load upon the armature, so that the machine maintains its excitation.

Another feature of my invention consists in placing the exciting-winding only at that portion of the armature that is idle on very heavy loads, so that the maximum effect of the exciting-winding is at all times obtained.

In order to avoid a lateral strain on the shaft, which would occur if the portions of the armature-winding cut out of circuit were not symmetrically positioned, I so arrange the armature-sections and their terminal connections that diametrically opposite armature-sections may be cut out of circuit.

My invention will best be understood by reference to the accompanying drawings, in which—

Figure 1 shows diagrammatically a self-

exciting alternating-current generator arranged in accordance with my invention, and Figs. 2 to 6 show some of the terminal connections which may be obtained with a machine arranged as in Fig. 1.

In Fig. 1, A represents the armature-body, which for the sake of simplicity is shown as a Gramme ring. The armature-winding is divided into four sections A', A², A³, and A⁴, which are relatively displaced around the armature. From each section leads are brought out to a terminal board. Thus the section A' is connected to the terminals t', section A² to terminals t², &c. F represents the field structure provided with the usual field-coils (indicated by f) and also provided with a rectifying-commutator C and commutator-brushes b. The arrangement of commutator and brushes which is shown in the drawings is that which I have fully described in a former patent, No. 789,476, issued to me May 9, 1905; but to facilitate the understanding of my present invention I shall briefly describe the arrangement here. The brushes b are given what I may term a "polyphase arrangement" on the commutator. The particular arrangement shown is three-phase, comprising three brushes displaced from each other by one hundred and twenty electrical degrees. Each of the commutator-segments is substantially equal in length to the distance between brushes, so that at the instant a segment is leaving one brush it makes contact with another brush. The machine shown in the drawings being a four-pole generator, four commutator-segments are employed, opposite segments being cross-connected.

The brushes b are supplied from a three-phase auxiliary exciting-winding carried by the armature. The phases of this winding are indicated by reference-letters a', a², and a³, respectively. Each phase, as shown, consists of two coils arranged diametrically opposite each other. One terminal of each phase is connected to a brush, and the other terminals are connected to each other in star or Y connection through the three-arm rheostat R, by means of which the field excitation may be varied. The three arms of the rheostat are adapted to cut varying portions of resistances r into series with the auxiliary exciting-winding. In the position shown all resistance is cut out of circuit except the resistances r', which may be left permanently in circuit in order to oppose any tendency to the flow of short-circuit current when two commutator-brushes are momentarily short-circuited by a commutator-segment. The brushes are so arranged, as disclosed in my former application, that this short-circuiting occurs at the moment when the voltages in the two phases short-circuited are approximately equal, so that no short-circuit current of any appreciable amount can flow. If the

rheostat is moved in a clockwise direction, as viewed in Fig. 1, the resistances r will be cut into circuit with the auxiliary exciting-winding and the excitation will be gradually reduced in the usual manner. If this movement is continued beyond the last contact of the resistances r, the high resistances r² are thrown into the field-circuit, thereby increasing the resistance in the field-circuit above the critical amount, so that the machine loses its excitation entirely. With this arrangement no field-switch is required, since the machine may be excited and put out of service by the rheostat-handle, and the arcing that occurs when a field-circuit is broken is wholly avoided.

With the arrangement as described above it is obvious that a considerable range of current and voltage may be obtained by varying the connections of the armature-sections to the work-circuit. Thus if the terminal connections are as shown in Fig. 2 all four armature-sections are connected in parallel to the work-circuit. The machine-terminals are indicated at T T. If the connections are as indicated in Fig. 3, the sections A' and A³ are connected in parallel with each, and the sections A² and A⁴ are also connected in parallel, the two groups being connected in series. The voltage is thus twice as great as that obtained in Fig. 2. Fig. 4 shows the connections with all the sections in series. This connection would be employed for long pipes of small diameter. In the case of very short pipes of large diameter the connection shown in Fig. 5 is employed. With this connection the sections A² and A⁴ are cut out of circuit, while the sections A' and A³ are connected in parallel to the work-circuit. Thus the portions of the armature on which the exciting-winding is carried are idle, as far as the main armature-current is concerned, and consequently however large the amount of current flowing in the sections A' and A³ the auxiliary exciting-winding is affected to a very small extent by the armature reaction. The machine is thus enabled to maintain its load even on a complete short circuit. Moreover, it will be seen that since the armature-sections, which are out of circuit, are diametrically opposite each other the magnetic pull of the field on the armature is balanced on all diameters, so that there is no tendency to strain the shaft. Fig. 6 shows still another connection in which the sections A² and A⁴ are still out of circuit, while the sections A' and A³ are connected in series to the work-circuit. This arrangement would be employed for pipes of a somewhat greater length or a somewhat smaller diameter than those for which the arrangement shown in Fig. 5 is suited.

I have described my invention with a view to its application in thawing pipes, since this type of work affords a good illustration of the

advantages my invention offers; but it will of course be understood that my invention is in no way limited to this particular application, but may be used to advantage wherever al-

5 ternating current varying over wide ranges in current and voltage is required. Furthermore, while for the sake of simplicity I have illustrated my invention diagrammatically it will be understood that in practice any 10 well-known type of machine may be employed for the purposes of my invention. Consequently I do not desire to limit myself to the particular construction and arrangement of parts here shown, but aim in the ap- 15 pended claims to cover all modifications which are within the scope of my invention.

What I claim as new, and desire to secure by Letters Patent of the United States, is—

1. In an alternating-current generator, a 20 field-winding provided with a rectifying-commutator and brushes, an armature-winding arranged in sections, means for connecting said sections in varying relations to the work-circuit, and an auxiliary exciting-wind- 25 ing carried by the armature and connected to said brushes.

2. In an alternating-current generator, a 30 field-winding provided with a rectifying-commutator, a polyphase arrangement of brushes bearing on said commutator, an armature-winding arranged in sections, means for connecting said sections in varying relations to the work-circuit, and a polyphase auxiliary exciting-winding carried by the armature 35 and connected to said brushes.

3. In an alternating-current generator, a 40 field-winding provided with a rectifying-commutator and brushes, an armature-winding arranged in sections, an auxiliary exciting-winding carried by the armature and connected to said brushes, and means for cutting a portion of the sections of the armature-windings out of circuit when currents of large volume and low voltage are required.

4. In an alternating-current generator, a 50 field-winding provided with a rectifying-commutator, a polyphase arrangement of brushes bearing on said commutator, an armature-winding arranged in sections, a polyphase auxiliary exciting-winding carried by the armature and connected to said brushes, and means for cutting a portion of the sections of the armature-winding out of circuit when currents of large amount and low voltage are required.

5. In an alternating-current generator, a 60 field-winding provided with a rectifying-commutator and brushes, an armature-winding comprising a plurality of relatively displaced sections, means for connecting all or a portion of said sections to the work-circuit, and an auxiliary exciting-winding ex-

tending over only a portion of the armature and connected to said brushes.

65

6. In an alternating-current generator, a field-winding provided with a rectifying-commutator, a polyphase arrangement of brushes bearing on said commutator, an armature-winding comprising a plurality of relatively displaced sections, means for connecting all or a portion of said sections to the work-circuit, and a polyphase auxiliary exciting-winding extending over only a portion of said armature and connected to said 75 brushes.

7. In an alternating-current generator, a field-winding provided with a rectifying-commutator and brushes, an armature-winding comprising a plurality of relatively displaced sections, means for cutting a portion of said sections out of circuit and connecting the remaining sections to the work-circuit, and an auxiliary exciting-winding carried by the idle portion of the armature 85 and connected to said brushes.

8. In an alternating-current generator, a field-winding provided with a rectifying-commutator, a polyphase arrangement of brushes bearing on said commutator, an armature-winding comprising a plurality of relatively displaced sections, means for cutting a portion of said sections out of circuit and connecting the remaining sections to the work-circuit, and a polyphase auxiliary exciting-winding carried by the idle portion of the armature 95 and connected to said brushes.

9. In an alternating-current generator, a field-winding provided with a rectifying-commutator and brushes, an armature-winding comprising a plurality of relatively displaced sections, means for cutting diametrically opposite sections out of circuit and connecting the remaining sections to the work-circuit, and an auxiliary exciting-winding carried by the idle portion of the armature 105 and connected to said brushes.

10. In an alternating-current generator, a field-winding provided with a rectifying-commutator, a polyphase arrangement of brushes bearing on said commutator, an armature-winding comprising a plurality of relatively displaced sections, means for cutting diametrically opposite sections out of circuit and connecting the remaining sections to the work-circuit, and a polyphase auxiliary exciting-winding carried by the idle portion of the armature 115 and connected to said brushes.

In witness whereof I have hereunto set my hand this 4th day of May, 1905.

ERNST F. W. ALEXANDERSON.
